Patented Nov. 15, 1927.

UNITED STATES PATENT OFFICE.

WALTER LYTTON, OF CHICAGO, ILLINOIS.

COMBINED RADIO RECEIVING SET AND SOUND-AMPLIFYING HORN.

Application filed June 10, 1922. Serial No. 567,383.

The invention relates to combined radio receiving sets and phonographs, and broadly refers in this phase thereof to the connection of the audio-frequency circuit of the radio receiving set with the ordinary tone arm or the horn of a phonograph, the parts being constructed and arranged in such a way that the two apparatus may be operated independently of each other, in accordance with the respective laws of their structure.

My invention is herein shown as embodied in and adapted to a complete phonograph, and the details of the invention will be hereinafter described in connection with the regular elements of a phonograph; but it will be understood that the invention is capable of similar adaptations to a sound wave amplifying horn of other specifically different forms. Certain of the features of construction are particularly adapted to a regular phonograph set and are herein claimed as such.

When the invention is adapted to a phonograph tone arm or horn, a valve in the tone arm is employed, which is adapted to be so adjusted, when the phonograph is independently used, to establish free communication between the phonograph reproducer and the horn, and is adapted to be adjusted to cut off such communication when the horn phone is in circuit with the audio-frequency circuit; and said valve is preferably constructed so that when it is adjusted to cut off communication between the reproducer and the horn there will be established free communication between the horn phone and the horn through a conduit free from sharp angular turns.

The circuit connections enable the person operating the combined apparatus to tune the audio-frequency circuit to the incoming radio frequency oscillations in the usual manner of tuning a radio receiving instrument, which can better be accomplished than when the tone arm or horn phone is connected in the audio-frequency circuit of the receiver. When such tuning has been accomplished, the phone of the tone arm or horn can be quickly connected in the audio-frequency circuit of the receiving set, and the head piece phones disconnected therefrom, so that the sound waves produced by phone at the tone arm or horn are modified as loud speaking tones, with a minimum effort and by means which do not affect the tuning of the radio circuits.

As shown in the drawings: Figure 1 is a front elevation of a cabinet constructed to support and enclose a combination radio receiving set and phonograph embodying my invention, the doors and covers being shown in their open position. And Figure 2 is a detail of the connection of the tone arm or horn phone and a valve for opening and closing the tone arm.

Of the drawings referring to the construction shown in Figures 1 and 2, 10 designates, as a whole, a cabinet provided with two compartments arranged side by side to receive and support the radio receiving set designated, as a whole, by 11, and a portion of the tone arm 12 and horn 13. The doors 14 which close the compartments and the swinging covers 15 are shown in their open positions.

The parts of the radio receiving set disclosed in Figure 1 are mounted on a panel 16. Of the parts which are thus shown 17 designates, as a whole, parts of the detector which may be of any suitable type, and 18 80 and 19 the parts of a two stage audio-frequency amplifier.

The head phones 20 are connected by the usual cord 21 to the audio-frequency amplifier circuit through any suitable connection indicated as a whole by 22. Such as a plug and jack connection. The horn phone or reproducer 23 is also arranged to be connected through a cord 24 in the audio-frequency amplifier circuit in any suitable manner. 90 Other switch connections are diagrammatically indicated at 25 and 26, the presence or use of which will depend upon the particular type of radio receiving set employed.

In both the constructions shown valves 95 are employed for opening and closing the conduits between the reproducer and horns. The valve 45 is a slide valve, to extend across the horn thoroughfare in one adjustment, and has a depending part 41 adapted in another adjustment to close the sound chamber 67 to the horn. Said valve and sound chamber is movable in suitable guides in the box or enclosure 39, and into and out of the reduced conduit of the horn 13. It is operated by a handle 46 which extends through a suitable guide in the adjacent cabinet wall. When said valve 45 occupies the position shown in full line the conduit or thoroughfare between the reproducer and horn 110 of the phonograph is fully open to permit free passage of the sound waves from the re-

producer to the horn. The shape of the valve 45, including the member 41', is such as to close off communication between the reproducer 23 and the horn when said valve 5 occupies its full line position. When said valve occupies the dotted position indicated in Fig. 2, the horn thoroughfare is cut off from the reproducer, and the outlet conduit 38 of the horn phone is in free communication with the horn. When the valve is in an intermediate position either or both reproducers may be used; and the valve may thus be used to modify the sounds from either reproducer. The surfaces of the valve 15 and sound chamber walls are so designed as to produce flaring and curved surfaces against which the sound waves impinge and to avoid sharp angles, which would, if present, impair the transmission of the sound 20 waves.

It is believed that the operation of the combined amplifying horn and radio receiving set will be evident from the description of the construction and the statements of 25 operation hereinabove set forth, and need not be repeated except to say that the construction is such as to produce in a very compact and simple way a loud speaking receiving set in combination with the horn of 30 a phonograph, or other suitable horn structure. It produces a construction which facilitates the tuning of the radio apparatus when adapted to a loud speaking horn effect 35 afforded by the phonograph, or other horn, and also affords a construction which permits the use of either the phonograph or the radio receiving set to operate independently in accordance with the laws of their respective structures.

It may be observed that the circuit of the receiving set can be tuned, when using the ear phone 20, without the disturbing harsh noises which would be emitted from the horn if the horn phone be in circuit with the audio-frequency output circuit. However, such tuning may be effected while listening, through the horn, if desired, and without the use of head piece phones.

I claim as my invention:

1. A radio sound reproducer in combination with a phonograph reproducer, a conduit connected with each of said reproducers, one of said conduits being slidably mounted, an amplifying horn, the outlet of each of said conduits being operatively connected with the inlet of the amplifying horn, and means for sliding said conduit alternately closing partly or entirely either of 50 the outlets of said conduit.

2. A cabinet including an amplifying horn having an inlet, a radio sound reproducer, and a phonograph sound reproducer mount-

ed in said cabinet, a conduit operatively connected with each of said reproducers, the outlet of each of said conduits being operatively connected with the inlet of said horn, means for closing the outlet of each of said conduits and means for operating said closing means said operating means extending to outside of said cabinet.

3. A sound amplifier comprising two sound reproducers, a conduit leading from each reproducer, a common conduit, each of said first mentioned conduits being operatively connected to said common conduit, and an amplifying horn connected to said common conduit, the axes of the portions of said two conduits adjacent their points of connection to said common conduit being parallel; whereby the two trains of sound waves are propagated in the same direction from said conduits into said common conduit, and means for alternately closing said conduits.

4. An article of manufacture comprising an amplifying horn having an inlet, a conduit fixed to said horn and having an inlet and an outlet, a slidably mounted second conduit associated with said horn and having an inlet and an outlet; means for sliding said second conduit, for operatively connecting either of said conduit outlets with said horn inlet; a phonograph sound reproducer fixed to the inlet of one of said conduits, and a radio sound reproducer fixed to the inlet of said other conduit.

5. An article of manufacture comprising a horn having an inlet, a conduit fixed to said horn and having an outlet, the outlet of said conduit facing the inlet of said horn, and a second conduit slidably mounted and having an outlet, and means for sliding said conduit from one position to another when said second conduit is in one position its outlet registering with the inlet of said horn and closing the outlet of said other conduit, and when said second conduit is in another position the outlet of the other conduit being open and the outlet of said second conduit being closed.

6. The combination of a radio sound reproducer, a phonograph reproducer, a conduit connecting with each of said reproducers, one of said conduits being slidably mounted, an amplifying horn, means for sliding said slidably mounted conduit into and out of registry with the inlet of the amplifying horn, the outlet of the other conduit being operatively connected with the inlet of the amplifying horn.

In witness whereof I claim the foregoing as my invention, I hereunto append my signature this seventh day of June, 1922.

WALTER LYTTON.
